UNITED STATES PATENT OFFICE.

JAMES DANIEL MIDSON, OF SOUTH BRISBANE, QUEENSLAND, AUSTRALIA.

PUZZLE.

SPECIFICATION forming part of Letters Patent No. 787,204, dated April 11, 1905.

Application filed July 7, 1904. Serial No. 215,572.

To all whom it may concern:

Be it known that I, JAMES DANIEL MIDSON, a subject of the King of Great Britain, residing at South Brisbane, Queensland, Australia, have invented certain new and useful Improvements in Puzzles, of which the following is a specification, such as will enable those skilled in the art to which it appertains to make and use the same.

The object of this invention is to provide an improved puzzle which is simple in construction and comparatively inexpensive and the solution of which is difficult, but may be accomplished by the exercise of care, skill, and ingenuity in the manipulation of the device, a further object being to provide a device of the class specified which is particularly designed to amuse both old and young.

The invention is fully disclosed in the following specification, of which the accompanying drawings form a part, in which the separate parts of my improvement are designated by suitable reference characters in each of the views, and in which—

Figure 1 is a perspective view of my improved puzzle; Fig. 2, a horizontal section on the line 2 2 of Fig. 3, and Fig. 3 a vertical section on the line 3 3 of Fig. 2.

In the practice of my invention I provide an oblong box or casing α , comprising a bottom α^2 , side walls α^3 , and end walls α^4 . At each end of the box or casing is a transversely-arranged house or inclosure b , formed by the end walls α^4 of the box or casing, the side walls α^3 thereof, a transversely-arranged front wall b^2 , and a roof or cover b^3 . The front walls b^2 of the houses or inclosures b are provided centrally with openings or doors b^4 , and in the opposite side portions of the said houses or inclosures and resting on the bottom α^2 are placed blocks b^5 , the inner or adjacent faces of which are inclined from the end walls α^4 forwardly and inwardly and join or connect with the front walls b^2 , as shown at b^6 , so as to form compartments b^7 , the side walls of which converge forwardly and inwardly toward the doors or openings b^4 , but do not extend entirely to said doors.

Within the box or casing α is placed a plurality of spherical balls or bodies, which, as

shown in the drawings, are eight in number and half of which are colored, so as to distinguish them from the other half, all of said balls or bodies, as shown in the drawings, being colored, a part of them being colored red 55 and the other part blue; and the solution of the puzzle consists in manipulating the device so that the balls or bodies of one color will be lodged in the compartment b^7 of one of the houses or inclosures b and the remaining balls 60 or bodies in the compartments b^7 of the other house or inclosure b . This solution is exceedingly difficult by reason of the shape of the compartments b^7 and by reason of the fact that the balls or bodies are free to roll over 65 the surface of the bottom α^2 .

It will be seen that the front walls of the compartments b^7 consist only of the narrow upright portions b^8 of the front walls b^2 of the houses or inclosures at the opposite sides of the doors b^4 , and while these narrow upright walls will aid in holding three of the balls in position in one of said compartments if the box or casing be properly held or tilted slightly to one side four or more of said balls 75 cannot be held in one of said compartments, except on the opposite sides of the door thereof, and this necessitates an exact adjustment of the position of the box or casing and careful and accurate manipulation thereof in order 80 to lodge all the balls of one color in one compartment and all those of the other color in the other compartment. The solution may, however, as hereinbefore stated, be accomplished by the exercise of care and skill in 85 the manipulation of the device, and in practice I prefer to provide the front walls b^2 of the houses or inclosures b with openings or windows d at the opposite sides of the doors b^4 ; but these openings or windows have not 90 function and are only added for the purpose of ornamentation.

By reason of the covers b^3 of the houses or inclosures b the partitions in said houses or inclosures are concealed, and the shape and 95 dimensions of the compartments therein are also concealed, and this renders the solution of the puzzle much more difficult than would appear from a casual inspection of the device.

It will be observed that the box or casing α 100

is oblong and rectangular in form; but various modifications in the form of the box or casing may be made without departing from the spirit of my invention or sacrificing its advantages. It will also be observed that there is an open space *e* between the houses or inclosures *b*, which may be of any desired dimensions and the bottom of which is flush with the bottoms of the compartments *b'*, and, if desired, a transparent cover may be placed over the open space *e*.

Having fully described my invention, what I claim as new, and desire to secure by Letters Patent, is—

15 A puzzle, comprising a box or casing having transversely-arranged inclosures at the opposite ends thereof and within which are central compartments, the front walls of said inclosures being provided with openings or

doors which communicate with said compartments, and the side walls of said compartments being inclined from the outer ends of the box or casing inwardly and forwardly to the front walls of said inclosures, said inclosures and compartments being also provided 25 with opaque covers and a plurality of balls or bodies placed in said box or casing part of which are distinguished from the others, substantially as shown and described.

In testimony that I claim the foregoing as 30 my invention I have signed my name, in presence of the subscribing witnesses, this 3d day of June, 1904.

JAMES DANIEL MIDSON.
